UNITED STATES PATENT OFFICE.

AURELIUS MARCUS RENZETTI AND DEE CARLTON BROWN, OF PHILADELPHIA, PENNSYLVANIA, ASSIGNORS TO STUTZ MOTOR CAR COMPANY OF AMERICA, INC., OF INDIANAPOLIS, INDIANA, A CORPORATION OF NEW YORK.

DESIGN FOR A RADIATOR CAP.

Application filed November 14, 1925. Serial No. 15,422. Term of patent 7 years.

To all whom it may concern:

Be it known that we, AURELIUS M. RENZETTI and DEE CARLTON BROWN, citizens of the United States, residing at Philadelphia, in the county of Philadelphia and State of Pennsylvania, have invented certain new, original, and ornamental Design for a Radiator Cap, of which the following is a specification, reference being had to the accompanying drawing, forming a part hereof.

Figure 1 is a front elevation, Fig. 2 a rear elevation and Fig. 3, a side view of a radiator cap, showing our new design.

We claim:

The ornamental design for a radiator cap, as shown.

In testimony whereof we each affix our signatures.

AURELIUS MARCUS RENZETTI.
DEE CARLTON BROWN.
